CLAIM

The ornamental design for a bookmark light, as shown and described.

DESCRIPTION

FIG. 1 is a perspective view showing a bookmark light having our new design, with the light in retracted, non-operative position;

FIG. 2 is a left-end view thereof;

FIG. 3 is a right-end view thereof;

FIG. 4 is a top plan view thereof;

FIG. 5 is a right side edge view thereof;

FIG. 6 is a bottom plan view thereof;

FIG. 7 is a left side edge view thereof; and,

FIG. 8 is a perspective view showing the bookmark light in its extended, operative position.

FIG. 1

FIG. 2

FIG. 3
